UNITED STATES PATENT OFFICE

PETER GYSBERT THOMAS DE VILLIERS, OF PRETORIA, TRANSVAAL, UNION OF SOUTH AFRICA, ASSIGNOR OF ONE-HALF TO MESSRS. ROGERS-JENKINS & CO. (PTY.) LTD., OF DURBAN, NATAL, UNION OF SOUTH AFRICA, A COMPANY REGISTERED IN THE UNION OF SOUTH AFRICA

AUTOMATIC TELEPHONE CALL BOX

Application filed February 21, 1930, Serial No. 430,240, and in Union of South Africa October 4, 1929.

This invention relates to improvements in an automatic telephone call box and has for its object to provide a device which switches and controls telephone calls from public call offices in automatic telephone areas.

Certain improvements in automatic telephone call boxes have been described in my British Patent No. 162,639, and reference is, therefore, made to these specifications in order to make clear the present invention.

The present invention may be adapted for use in connection with a standard automatic telephone dial to which is suitably coupled a mechanism for the purpose of our invention. The nut and lock-nut attached to the back of the shaft of automatic telephone dials at present in use is utilized in this invention to engage in a corresponding socket in the nature of a box spanner attached with a flexible joint to a main spindle in our mechanism or alternatively the back of the shaft or any other moving part of the dial can be coupled to such main spindle in any known manner.

To this spindle a pawl is fitted in any known manner to operate a ratchet wheel, causing it to move in an anti-clockwise direction through a partial revolution, when the dial is turned in a clockwise direction. The pawl may be so adapted as to cause the wheel to move forward a fixed number of teeth for each movement of the dial, depending on the size and nature of the wheel and its teeth. When the dial has been operated a certain number of times, say nine times, then the pawl and ratchet wheel reach a position in relation to each other where no teeth are provided on the ratchet wheel and the mechanism is thus put out of operation, thereby preventing unnecessary strain on a spring member disposed behind the ratchet wheel for the purpose of bringing it back to its normal position. The ratchet wheel is kept in position by a holding pawl connected with and controlled in any known manner by the switch arm of the telephone handset. Upon replacing the telephone handset after use the holding pawl is released, thus enabling the spring member under compression to bring the ratchet wheel back to its normal position.

In lieu of the ratchet wheel a toothed bar

or rack may conveniently be employed, the only difference being that the pawl on the main spindle will now move the rack in a horizontal or any required linear direction.

On the same spindle as the ratchet wheel is mounted a cam on which a bead or the like insulator travels, governing electric contacts of the automatic arrangement. Adjacent the first cam a second cam of different form is mounted on the spindle. A magnet of any type but preferable a permanent magnet for the simplification of the mechanism is disposed on the second cam. As the ratchet is rotated this second cam rotates permitting the magnet to drop under its own weight or alternatively to be drawn down by a spring member or in some other suitable manner and taking up a final position after a fixed number of movements preferably four of the dial, so that a trip bell-crank lever (described in my British Patent No. 162,639) adheres to the magnet when operated by a coin.

This trip in its usual position short circuits the telephone transmitter acting as a shunt across the transmitter terminals so that speech on the call side is only possible after the coin has been inserted and the short circuit broken. If less than four or the specified number of digits is dialled and the coin inserted in the call box, the contacts operated by the first cam on the ratchet wheel shaft connects the contact screw of the trip lever in the manner hereinafter described with reference to the drawings which enables the exchange operator to hear the buzz of the vibrator as disclosed in my British Patent No. 162,639. The call box may, therefore, be used for manual trunk telephone operating as well.

In order that my invention may be more readily understood and carried into practice reference is hereby made to the accompanying drawings wherein

Figure 1 is a side elevation of the mechanism of the invention;

Figure 2 is a section on A—B of Figure 1;

Figure 3 shows details of the electric contacts operated by the first cam;

Figure 4 is a section on C—D of Figure 1 omitting the parts shown in Figure 2;

Figure 5 is a diagram of the connections.

Referring to these drawings wherein like reference numbers indicate the same parts wherever occurring throughout all the views, 1 indicates the main spindle, to which is attached the shaft of the standard dial which in the embodiment illustrated in the accompanying drawings engages a socket of box spanner form 2 by means of flexible coupling 3. On the shaft is further mounted the pawl 4 which engages the teeth on ratchet 5 when spindle 1 is rotated by the operation of the dial.

On shaft 6 of ratchet 5 is also mounted cam 7 adjacent the ratchet wheel on to which bead or insulator 8 bears down. To this bead is attached common spring contact 8a of the electric circuit. This spring contact has contact points 9 and 10 respectively to close the electric circuits at 11 and 12 respectively on rotation of cam 7.

If less than four figures are dialled in an embodiment in which cam 7 is so adjusted that four figures must be dialled before conversation can proceed the contacts 9 and 11 will remain closed, so that if a coin is inserted at 13 it lifts the bell crank trip lever 14 momentarily on its way down enabling the exchange operator to hear the buzz between the contact screw 15 and vibrator contact 16.

A second cam 17 adjacent cam 7 also mounted on shaft 6 permits the magnet 18 which is disposed on cam 17 to drop to its new position indicated by dotted lines at 19 after four numbers or the specified number of digits have been dialled so that when the coin is inserted at 13 it strikes the trip lever 14 on its way down which then swings over and adheres to the magnet, thus breaking the shunt across vibrator 16 and lead from the contact 12, thus allowing conversation to proceed.

The telephone switch arm is designated 20 and operates the holding pawl 21 on ratchet 5 when the handset is removed from the switch arm hook. Stops 22 limit the position of the ratchet 5 and spiral spring 23 brings the ratchet back to its original position when pawl 21 is disengaged.

Referring to Figure 5, 24 indicates the contacts of the dial, and 25 the contacts operated by the switch arm 20. Receiver terminals are shown at 26 and transmitter terminals at 27. The rest of the circuit diagram is the usual diagram for an automatic telephone call box.

In operation the number required is dialled after removing the telephone handset from switch arm. If the number is one of four digits the ratchet wheel moves forward through a distance of 8 teeth, (if 2 teeth are taken when one figure of the number is dialled) the magnet 18 takes up its new position 19, permitting the trip lever 14 to adhere to it when the coin is inserted. Also contacts 10 and 12 will be closed, due to the bead 8 being now on the raised portion of cam 7.

The improvements herein set forth are not limited to the precise form of construction as described, but may be embodied in various forms without departing from the spirit and scope of the invention—e. g. contacts may be modified and the cams substituted by devices which would suit the same purpose.

What I claim is:

1. An automatic telephone call box of the type having a casing and operated by a standard automatic impulse dial on a shaft, a main spindle coupled to said dial shaft, a secondary spindle on said casing carrying a fixed ratchet wheel and a spring detent co-operating therewith, a pawl on the main spindle for operating said ratchet wheel, a cam fixed on said secondary spindle for operating transmitted contacts, a second cam on said secondary spindle, a bar magnet pivoted to said casing and resting in engagement with said second cam.

2. An automatic telephone call box of the type having a casing and operated by a standard automatic impulse dial on a shaft, a main spindle coupled to said dial shaft, a secondary spindle on said casing carrying a fixed ratchet wheel and a spring detent co-operating therewith and actuated by the switch arm, a pawl on the main spindle for operating said ratchet wheel, a cam fixed on said secondary spindle for operating transmitter contacts, a second cam on said secondary spindle, a bar magnet pivoted to said casing and resting in engagement with said second cam, and a bell crank trip lever pivoted at the junction of its two arms to said casing in such a position that one end thereof projects into said coin chute and is thereby tripped by the falling call coin to a position to be attracted and held by said bar magnet.

3. An automatic telephone call box of the type having a casing and operated by a standard automatic impulse dial on a shaft, a main spindle coupled to said dial shaft, a secondary spindle on said casing carrying a fixed ratchet wheel and a spring detent co-operating therewith, a pawl on the main spindle for operating said ratchet wheel, a cam fixed on said secondary spindle for operating transmitter contacts, a second cam on said secondary spindle, a bar magnet pivoted to said casing and resting in engagement with said second cam, and a bell crank trip lever pivoted at the junction of its two arms to said casing in such a position that one arm projects into said coin chute in the path of the inserted call coin, while the other arm in its normal position contacts with a vibrator contact completing thereby the short circuit across the transmitter terminals, which short circuit is opened by the tripping of said bell crank lever by the passage of the inserted call coin down the coin chute.

4. An automatic telephone call box of the type having a casing and operated by a

standard automatic impulse dial on a shaft, a main spindle coupled to said dial shaft, a secondary spindle on said casing carrying a fixed ratchet wheel and a spring detent co-
5 operating therewith, a pawl on the main spindle for operating said ratchet wheel, a cam fixed on said secondary spindle for operating transmitter contacts, a second cam on said secondary spindle, a bar magnet piv-
10 oted to said casing and resting in engagement with said second cam, and a bell crank trip lever pivoted to said casing and adapted to be tripped by a call-coin inserted in the coin chute, to a position to be attracted and held
15 by said bar magnet, said bar magnet being adapted to be progressively caused to move to a position to attract and hold the outer arm of said bell crank trip lever after a pre-
determined number of digits have been
20 dialled and said bell crank lever is tripped by the inserted call coin.

Signed at Johannesburg, South Africa,
this 14th day of January A. D. 1930.

PETER GYSBERT THOMAS de VILLIERS.
